[57] **CLAIM**

The ornamental design for a lamp, as shown and described.

DESCRIPTION

FIG. 1 is a perspective view of the lamp showing my new design;

FIG. 2 is a left side view thereof, the right side view being a mirror image.

FIG. 3 is a top view thereof.

The rear of the simulated rocket is identical to the sides; the rear of the plate which extends from the base is flat and unornamented.
